UNITED STATES PATENT OFFICE.

MARY MOUAT, OF MOUNT ROSKILL, AUCKLAND, NEW ZEALAND.

SANITARY APPARATUS.

1,103,890.

Specification of Letters Patent. Patented July 14, 1914.

Application filed February 27, 1913. Serial No. 751,091.

To all whom it may concern:

Be it known that I, MARY MOUAT, a citizen of the Dominion of New Zealand, and residing at Dexter avenue, Mount Roskill, in the Provincial District of Auckland, in the Dominion of New Zealand, have invented certain new and useful Improvements in Sanitary Apparatus, of which the following is a specification.

10 The invention relates to paper covers for closet seats and my object is to provide a new type of paper cover and mechanical means whereby a used cover is replaced by a fresh one.

15 According hereto, a reel of paper ribbon is perforated at regular intervals with openings corresponding with the opening in the seat. The periphery of each hole has radial cuts to permit the edge of the paper to fit 20 the bevel of the opening and the reel is preferably carried in a casing having a longitudinal slot through which the paper is drawn. The paper ribbon is led across the top of the seat, over a cylindrical drum and 25 is connected to a driven bobbin upon which the used paper is wound. The drum may have projecting spikes which prevent the paper ribbon from slipping. The drum is rotated when the lid of the seat is opened 30 or closed as may be arranged, by an escapement lever which engages a ratchet wheel upon the drum spindle, a friction spring or clutch being interposed if desired to prevent too great pull on the paper. Other 35 equivalent means, such as rack and pinion, or sprocket gear, or a system of levers may be employed to rotate the drum. The used paper bobbin is driven by an endless leather belt or other equivalent means from the 40 main drum spindle.

45 Coin freed mechanism may be employed to lock the lid or to lock the apparatus so that a change of paper cover is only effected after the insertion of a coin.

46 The drawing herewith illustrates the invention.

Figure 1 is a vertical transverse section thereof, taken in the line of the seat. Fig. 2 is a horizontal section, and Fig. 3 is a vertical section of the same, taken through the rear portion. Fig. 4, is a side elevation showing a coin released catch.

50 Referring to the drawing, the reel 1 of paper ribbon 1^a has perforations 2 at regular intervals, the perforations corresponding with the opening 4 in the seat 3. The per-

iphery of each perforation has radial cuts 5 to permit the paper 1^a to fit the bevel of the opening 4. The reel 1 of paper is carried in a casing 7 having a slot 8 through which the paper is drawn. The paper 1^a is led across the top of the seat 3 and over a drum 10 and is connected to a driven bobbin 11 upon which the paper is wound. The drum 10 may have projecting spikes which prevent the paper from slipping. When the lid 12 of the seat is opened or closed the bobbin 11 is rotated by an escapement mechanism comprising a lever 13 attached to the lid 12, and a spring operated pawl 14 pivoted upon an arm 15. A link 16 connects the lever 13 to the arm 15. The pawl 14 engages a ratchet wheel 17 fixed upon a spindle 18, and a bevel wheel 20, integral with the ratchet wheel 17, is mounted upon the spindle 18. A bevel pinion 21, mounted upon the spindle 22 of the drum 10, gears with the wheel 20, any suitable means being interposed between the pinion and the spindle 22 to prevent too great a pull being exerted upon the paper.

The paper is kept taut by means of a tension roller 23, mounted in bars 24 slidable on rods 25. The bars rest upon springs 26, which afford the necessary tension by pressing the bars upward. The spindle of the reel 1 is retained in its bearings 27 by flat springs 28 which yield to allow the reel to be removed. A bell crank lever 29 pivoted upon a pin 29^a holds the spindle 28 in its bearing and is readily turned aside for the purpose of removing the bobbin 11. The bobbin 11 is driven by a belt 30 passing around grooved pulleys 31 and 32 fixed upon the spindles 22 and 23 respectively.

The lid 12 may be provided with a catch 34 adapted to be engaged by a latch 35 pivoted to the side of a casing 36. The latch extends below a chute 37 having a mouth-piece 38 adapted to admit singly coins 39 of any desired denomination. When a coin of the desired denomination is dropped into the chute 37, the latch 35 is tipped as shown by dotted lines in Fig. 4, thereby setting free the latch 35, allowing the coin to fall into the casing 36, and the lid 12 to be closed.

What I do claim and desire to secure by Letters Patent of the United States is:—

The combination with a closet seat and lid therefor, of a paper bearing roll removably mounted to one side thereof, a drum rotatably mounted on the opposite side of

said seat over which the paper is adapted to pass, a bobbin upon which the paper is adapted to be wound, two pairs of parallel rods, a member having a bearing therein carried by each pair of rods, a roller carried by said bearings, spring means for holding said bearing containing members normally at one end of said parallel rods, said roller being adapted to bear against the

paper intermediate said drum and bobbin 10 and means for rotating said bobbin.

In testimony whereof I have signed my name to this specification in the presence of two witnesses.

MARY MOUAT.
